UNITED STATES PATENT OFFICE.

GORDON T. WHELTON, OF NEW YORK, N. Y.

ORDNANCE PROJECTILE

Application filed November 17, 1921. Serial No. 515,895.

To all whom it may concern:

Be it known that I, GORDON T. WHELTON, a citizen of the United States, residing at New York city, in the county of New York, and State of New York, have invented certain new and useful Improvements in Ordnance Projectiles, of which the following is a specification, reference being had therein to the accompanying drawing.

This invention is an improvement in ordnance projectiles, and relates especially to the class of projectile adapted to be discharged from a rifle and to undergo a timed explosion, to deliver and discharge a missile adapted to spread laterally so as to cover a large area in its continued flight. Projectiles of this class are useful for attacking aircraft, barbed wire entanglements, wireless or signalling plants or lines, and the like.

The general object of the present invention is to afford a projectile of the class referred to which will be more efficient and practical in operation than those heretofore attempted. A particular object is to afford a system of weights, freed by the explosion of the projectile and adapted to spread by centrifugal force, but connected in an effective manner by wires so as to constitute a missile of extensive lateral area, thus more capable of reaching its mark, and of such character that contact with the mark at any point causes the destructive effect of the entire missile to be applied to the mark or object being attacked. Other objects and advantages of the present improvement will be specified in the hereinafter following description of an embodiment thereof or will be apparent to those skilled in the art.

To the attainment of the above referred to objects and advantages the present invention consists in the novel projectile, and the novel features of construction, combination, arrangement and detail herein shown or described.

In the accompanying drawings, illustrating one or more embodiments of the present invention, Fig. 1 is a central longitudinal section.

Fig. 2 is a top plan view of the projectile seen in Fig. 1.

Fig. 3 is a cross section on the line 3—3 of Fig. 1.

Fig. 4 is a plan view of certain interior parts detached.

Fig. 5 is a section taken on the line 5—5 of Fig. 4.

Fig. 6 is an enlarged elevation partly in section of certain details seen in Fig. 1, namely, the weight releasing devices.

Fig. 7 is a view similar to Fig. 6 of a modified release device superior for certain purposes.

Fig. 8 is a diagram indicating a practical use of my invention.

Fig. 9 shows a modified form of missile or connected weights and wires.

Fig. 10 is a central longitudinal section similar to Fig. 1, but showing the disposition of the parts after the explosion of the projectile and immediately following the release of the weights.

Fig. 11 shows a slightly later stage in which the wire coil and central weight have detached themselves from the parts which carry them in the projectile.

Fig. 12 is a perspective view of a detail.

In the diagram of Fig. 8 is indicated an anti-aircraft rifle 15 which has just fired a projectile embodying this invention toward an aeroplane 16. The exploded or empty shell 17 is shown as having discharged the missile 18 at a point short of the aeroplane, and the missile is shown as having expanded due to its rotation and the centrifugal force of the peripheral weights 19. The missile may consist of the centrifugal weights 19, with wires 20 interconnecting them, which are preferably composed of piano wire, but could consist of chains or other connectors, and a central member or weight 21. It will be understood that the arrangement of wires and weights could be variously modified; for example, in Fig. 9 the central weight is dispensed with and the wires are differently arranged.

In all cases, however, the expanded missile should be of such form as to present considerable lateral reach, so as to greatly increase the chances of contacting the mark. Upon any part of the missile reaching the aeroplane the wires and weights through their momentum will encompass the aeroplane and effect substantial damage.

The projectile shell 17 is seen, in Figs. 1, 10 and 11, to be generally cylindrical, and its base is provided with a plurality of circumferential rings 23, of soft metal, to engage the rifling of the ordnance piece in the usual manner. Within the base of the projectile is indicated a time fuse 24, screwed

into place, and directly above this is the explosion chamber 25 containing gun powder 26 of suitable quality. The interior of the projectile is divided into three chambers, the explosion chamber 25, just mentioned, the middle chamber 27 in which the coiled wires 20 of the missile are stored, and an upper or nose chamber 28 containing the weights 19 of the missile. The nose end 29 of the projectile, containing the weights 19, is constructed in such a way that on the explosion of the shell the weights may be discharged. For this purpose the projectile nose is weakened along the radial lines by a series of kerfs 30 which divide the conical nose into a series of sections 31, which in reality are separate, and each of which is readily broken away from the body 17 of the shell by reason of the formation of an interior circumferential groove 32 at the base of the nose.

The timed explosion of the powder in chamber 25 causes the discharge and ejection from the shell of everything located above the powder. These ejected parts include the parts of the missile and additionally other parts, which are so controlled as to be separated from the missile so that the latter will be free of impediment as it advances in the manner shown in Fig. 8. It will be understood that at the moment of explosion the pressure against the nose sections 31 will cause them to break off from the shell, as indicated in Fig. 10, thus giving a free advance to the weights and wires of the missile.

It is the plan of this invention to give the missile a rapid rotary movement, added to the rotation imparted by the rifle. For this purpose the interior of the shell 17 is formed with rifling or ribs 33. It will be noticed from Figs. 10 and 11 that these ribs start at their base with a very small incline, or none at all, and their pitch gradually assumes the effective angle indicated at the upper portion of these figures. By this arrangement the missile is started into rotation without abrupt action and gradually assumes its full rotation up to the time of discharge from the projectile.

The rifle ribs 33 are engaged by a follower or disc 35 initially located on top of the powder chamber. This rifle-engaging disc 35 is shown in Figs. 1 and 4, and in detail in Fig. 5. It is preferably built up of a central layer 36, composed of steel, with a lead disc 37 below it constituting a seal for the powder chamber, and a second lead disc 38 above it constituting a second seal, and giving a certain cushioning effect, preventing damage by the discharge. The disc 35 is one of the parts ejected from the interior of the shell but not intended to accompany the missile in its flight. Another such part is a central tube or core 40 which is shown square in form and rigidly connected to the disc 35. The lower exit of the hollow tube 40,

is provided with a stop or shoulder 41 consisting of a projecting part of the disc 35.

The central weight 21 is preferably apertured, as shown, so as to engage around the core 40 and initially it is located to rest upon the interior disc 35. The radiating wires of the missile may be connected to the central weight in the manner indicated in Fig. 5, the wires being threaded through apertures 42 in the weight and knotted to hold them in place.

The wires 20 are wound in an annular form, surrounding the core 40, and in such manner as to permit the wires to be readily reeled off from the upper end, as the weights 20 separate centrifugally, without entanglement. The upper end of each of the four wires is secured to one of the four weights by means of attaching ring 43 formed on each of the weights. These rings serve not only as attachments for the wires but also to cooperate with a releasing device or trigger as will next be explained.

The releasing device is herein shown as comprising a block 45 slideable within the hollow core or square tube 40. Upon the explosion of the shell this block, in its releasing action, is intended to be pulled downwardly through the tube and for this purpose a wire or chain 46 is shown attached at its upper end to the block and at its lower end secured at 47 to the base of the projectile.

Figs. 1, 10 and 11 successively show how the releaser block 45 is pulled relatively downwardly, first to effect the release of the weights, and finally, contacting the stop or shoulder 41, as seen in Figs. 11 and 12, to detach the disc and core from the unwinding missile. As shown in Figs. 1 and 6 the weights are initially held together by the rings 43 thereof engaging upon a series of hooks 49 pivoted to the top of the tube 40. The block 45, standing between the shanks 50 of the four hooks, locks them in the position shown. The relative descent of the release block 45 releases the hooks so that they can fall apart to the position shown in Fig. 10 and in dotted lines in Fig. 6. The hooks readily move together again as shown in Fig. 11 for the purpose of permitting the extraction of the core from the coiled wires 20. Fig. 7 shows a modified release in which a slightly different form of block, 45^a, is provided with upstanding pins 49^a upon which the rings 43 engage, and which are extracted from the rings by the relative pulling down of the block.

The operation of the described projectile may be as follows. The time fuse having been adjusted to act at the proper instant the rifle is discharged in a direction to attack the aircraft. Somewhat short of the target the fuse acts to explode the powder charge within the projectile. This produces

an upward thrust against the interior disc and the parts of the missile about it. The arrangement of the parts is considered advantageous, the coiled wires being in the middle chamber and the plurality of weights in the nose, which is weakened or otherwise constructed so as to open and deliver the missile upwardly. The explosion gives a new impetus to the forward propulsion and at the same time the rifling within the shell substantially increases the rotary action. The rifling is preferably of the special form prescribed and is of considerable length owing to the low position of the interior disc, which travels substantially the entire length of the body of the shell. The additional rotation in the missile thus afforded substantially increases the centrifugal force acting upon the weights. It will be noted that the weights and wires are at first compactly contained and held within the upper and middle chambers of the shell but upon discharge the weights are freely and simultaneously released by the described unlocking device, which however acts only after the nose of the projectile has broken open and permitted the entire missile to free itself from the shell. With the release of the weights the centrifugal force immediately throws them out as shown in Figs. 8 or 9 and at the same time the disc and core are automatically detached from the missile so that the latter is not encumbered with anything that might foul or prevent the free unwinding of the wires. Upon either a weight or a wire contacting the mark there results not merely the damage therefrom, but the remainder of the missile is caused to apply its entire destructive effect to the object attacked, the wires in some cases winding around portions of the object so as to throw the weights forcibly in different directions against various portions of the object. It will thus be seen that I have described an ordnance projectile embodying the principles and attaining the advantages of the present invention. Since many matters of design, arrangement, combination and detail may be variously modified without departing from the principles involved, it is not intended to limit the invention to such matters except in so far as set forth in the appended claims.

What is claimed is:

1. In an ordnance projectile, a hollow shell containing a powder charge and timed exploding means, and containing above the powder charge a spreading missile wholly separable from the shell, consisting of a plurality of weights adapted to spread centrifugally when released and a system of wires interconnecting the weights, together

with an interior device, independent of said missile and wires for normally locking said weights inwardly, and releasing them after their discharge.

2. In an ordnance projectile, a hollow shell containing a powder charge and timed exploding means, and containing above the powder charge a spreading missile wholly separable from the shell, consisting of a plurality of weights adapted to spread centrifugally when released and a system of wires interconnecting the weights, said weights each having a hooking extension, a central holding device normally engaging said extensions and means to release said device by the discharge of the missile from the shell.

3. In an ordnance projectile, a hollow shell interiorly rifled and containing a powder charge in its base and a timed exploding means, and containing above the powder charge a combined disk-and-core member, the disk thereof engaging the said rifling, and a spreading missile wholly separable from the shell, consisting of a plurality of weights adapted to spread centrifugally when released and a system of wires interconnecting the weights, said wires being initially curled around said core, and the weights being connected to the core, whereby upon explosion the disk and core are rotated and communicate the rotation to the wires and weights.

4. Projectile as in claim 3 and wherein the core is hollow and has a device at its upper end engaging and holding the weights, and a flexible connection passing through the core adapted to release said device by the discharge of the missile from the shell.

5. Projectile as in claim 4 and wherein the flexible connection is adapted to detach the core and disk from the missile after the release of the weights.

6. In an ordnance projectile, a hollow shell interiorly rifled and containing a powder charge in its base and a timed exploding means, and containing above the powder charge a spreading missile wholly separable from the shell, consisting of a plurality of weights adapted to spread centrifugally when released and a system of wires interconnecting the weights, a detachable member adapted to engage the rifling and be rotated thereby and associated with the missile so as to rotate the same, and a flexible connector arranged to detach the device upon the ejection of the missile from the shell.

In testimony whereof, I have affixed my signature hereto.

GORDON T. WHELTON
